CLAIM

The ornamental design for a dog crate furniture, as shown and described.

DESCRIPTION

FIG. 1 is a front perspective view of a dog crate furniture, showing my new design;

FIG. 2 is a rear perspective view thereof;

FIG. 3 is a front elevation view thereof;

FIG. 4 is a rear elevation view thereof;

FIG. 5 is a left side elevation view thereof; the right side elevation view being a mirror image of FIG. 5;

FIG. 6 is a top plan view thereof; and,

FIG. 7 is a bottom plan view thereof.

The broken lines in the drawings depict portions of the dog crate furniture that form no part of the claimed design.

1 Claim, 7 Drawing Sheets(56)
